[57] **CLAIM**

I claim the ornamental design for a port replicator for a notebook computer, as shown and described.

DESCRIPTION

FIG. 1 is a perspective view from above and the right of the port replicator for a notebook computer of my invention; FIG. 2 is a perspective view from the rear and above of the port replicator for a notebook computer of FIG. 1; FIG. 3 is a view similar to FIG. 1 wherein a notebook computer system is shown in broken lines for illustrative purposes only and forms no part of the claimed design; FIG. 4 is a front elevation view of the port replicator of FIGS. 1 and 2 on an enlarged scale; FIG. 5 is a rear elevation view of the port replicator of FIGS. 1, 2 and 4; FIG. 6 is a side elevation view from the left of the port replicator of FIGS. 1, 2, 4 and 5; FIG. 7 is a plan view from above of the port replicator of FIGS. 1, 2, 4, 5 and 6; FIG. 8 is a plan view from below of the port replicator of FIGS. 1, 2, 4, 5, 6 and 7; and, FIG. 9 is a side elevation view from the right of the port replicator of FIGS. 1, 2, 3, 4, 5, 6, 7 and 8.
